UNITED STATES PATENT OFFICE

SAMUEL L. DAUGHERTY, OF FORT MADISON, IOWA, ASSIGNOR TO W. A. SHEAFFER PEN COMPANY, OF FORT MADISON, IOWA, A CORPORATION OF DELAWARE

FOUNTAIN PEN DESK STAND

Application filed November 26, 1930. Serial No. 498,221.

This invention relates to a fountain pen desk stand and has special reference to a desk stand for holding fountain pens at various predetermined angular positions with respect to the base on which a receptacle for the fountain pen is mounted for universal movement thereon.

More particularly, this invention relates to a device comprising a base of comparatively heavy weight adapted to lie on the top of a table and having a receptacle for receiving and sealing apart from the atmosphere the writing point and ink feeding mechanism of a fountain pen, the receptacle being secured to a base in a manner to afford movement thereof into various positions of angular and rotatable adjustment.

It is desirable to hold a fountain pen in a position such that the ink therein flows toward the writing point and thereby to facilitate the flow of ink when starting to write. Also, the writing point and ink feeding mechanism should be kept in a moist condition with ink at the point free from contact with air. Again, it is desirable that the fountain pen be held at such a position that it may be readily grasped by the hand preparatory to writing without subsequent adjustment to any particular style. All of these features may be accomplished by the provision of a receptacle having a shoulder on which the end of the fountain pen rests to provide a chamber which is substantially air-tight, the receptacle being rotatably held at a predetermined angle or in a series of predetermined angular positions relatively to the base.

In an application assigned to the assignee of the present invention, filed October 20, 1930, and given Serial No. 489,824, and now Patent Number 1,860,853, May 31, 1932, a fountain pen desk stand is shown and described incorporating therein many of the characteristics disclosed in the structure presented herewith. The present invention is directed particularly to an improvement of the aforementioned application and is directed more particularly to the specific type of spring pressed plunger associated in the support for the receptacle and engaging the

positioning member therefor. The former invention, above identified, is directed to a post for providing a universal movement of the receptacle in which the post is lowered considerably and provided with a pivotal connection which is assembled from the inside of the post thereby avoiding the unsightliness of having the pivotal pin exposed to view. These features are likewise incorporated in the present invention, the pivotal means for the receptacle being assembled from the inside side of the construction. However, in order that the receptacle be firmly held in its various fixed adjusted positions with a minimum of effort being required to manually move the receptacle into a second fixed adjusted position, the ball bearing is provided in the spring pressed plunger. The compression of the spring may be made sufficiently great so that a subsequent adjustment is unnecessary.

One of the objects of this invention is to provide a fountain pen desk stand of the character indicated above wherein the pivotal means between the receptacle and support is assembled from within the support, the pivotal means including a ball bearing whereby a minimum amount of energy may be employed to move the receptacle to a changed position with a maximum gripping power for holding said receptacle in the initial position which needs no subsequent adjustment.

Other objects and advantages will herein-after be more particularly pointed out and for a more complete understanding of the characteristic features of this invention, reference may now be had to the following description when read in connection with the accompanying drawing, in which latter:

Fig. 1 is a side elevational view showing the base and supporting mechanism in section;

Fig. 2 is a fragmentary view taken on the line 2-2 of Figure 1; and

Fig. 3 is a central sectional view showing the ball in elevation of the plunger for engaging the positioning means of the receptacle.

Referring now more particularly to the

drawing, the device of this invention comprises a base 10 which is formed preferably of onyx or may be formed of marble, plate glass, statuary materials, or other materials or compositions having substantial mass and weight. Various configurations and shapes of bases may be made in order to enhance the beauty of the device which, of course, is desirable aside from the convenience and general utility of the device. The base may be provided with recesses for receiving clips, pins and other depressions for positioning statuary objects, and the like, which latter are common in these types of devices.

15 The base is provided with intercommunicating concentric apertures 11 and 12 extending between the bottom and top surfaces thereof for receiving a post 13, the latter comprising a head portion 14 and a shank portion 15. The outer end of the shank portion is externally threaded to receive a nut 16, which latter is tightened against spring washers in engagement with the shoulder formed by the intercommunicating apertures 20 11 and 12. The head 14 of the post bears against a washer 17, preferably of fiber, which latter bears against the base 10 in order to prevent chipping of the base when the post 13 is rotated.

30 The post 13 is provided with an internal axial bore 18, the outer end of which is internally threaded to receive a screw plug 19, the latter having a reduced extension 20 thereon for positioning a coil spring member 35 21 into which member the projection 20 extends. The upper end of the bore 18 is adapted to receive in slidably engagement therewith a plunger 22 which is held in an upper position against a positioning member 40 23 by means of the compression spring 21.

A receptacle 24 preferably formed of a pyroxylin plastic product or of any other well-known composition is formed with an upper end flared opening for receiving the writing 45 point end of the fountain pen, a shoulder at the lower end of the opening bearing against the end of the barrel to provide a chamber at the lower end of the receptacle to receive and to substantially seal the ink feeding mechanism and the writing point of the fountain pen.

The positioning member 23 having a scalloped periphery is secured to the end of the receptacle 24 as by means of having an internally threaded recess for receiving a screw member extending from the closed end of the receptacle. The scalloped periphery edge of the positioning member 23 is formed of arcuate portions, the centers of which portions 55 are preferably equi-distantly spaced from the aperture for the pivotal pin 25. The pin 25 extends through and beyond each face side of the positioning member 23 to form a pivotal mounting for the receptacle 24.

60 65 The upper end or head 14 of the post 13 is

provided with a slot 26 of sufficient width to permit the pivotal movement of the positioning member 23 therein, the width of the positioning member being slightly smaller than the diameter of the bore 18 to allow free passage therethrough. The pin 25 is mounted in a recess at the upper end of the bore 18 and extends across or laterally of the slot 26, the recess forming to the curvature of the circumference of the pin 25 thus providing a bearing portion against which the pin rests or is urged by the action of the plunger 22, which we will now describe in detail.

Referring now more particularly to Fig. 3, the plunger 22 is shown in cross section 30 as comprising a cylindrical body having a central recess 27 in its lower end of a sufficient diameter to permit the ready entrance of the compression spring 21, the spring seating against the material bounding the upper end of the recess. The upper end of the cylindrical body 22 is provided with a recess 28 of sufficient diameter to receive in a rotatable relation therein a ball bearing 29, the recess being sufficiently deep so that the upper end of the material surrounding the recess extends beyond the center of the ball. The cylindrical end is preferably tapered as at 30 in order that the material thereof may be readily formed against the ball in order that the latter may be loosely retained in the recess 28. Further, the recess may be provided with a drop or two of lubricating oil in order that the ball may freely revolve in its recess. It has been found that this slight amount of oil will permit a pivotal movement of the receptacle 24 for a substantial period of time without becoming dissipated from the recess. The ball, which is preferably of steel, is prevented from corroding and gives a maximum of efficiency.

The ball 29 is urged into one of the arcuate portions of the scalloped periphery of the positioning member 23 by reason of its association with the spring pressed plunger 110 22 to position the receptacle 24 in one of its various fixed adjusted positions wherein the ink in the fountain pen flows toward the writing point thereof. When it is desired to move the receptacle 24 into one of its other fixed adjusted positions, the plunger 22 is urged against the tension of the coil spring 21 by manual force whereafter when the force is released, the plunger urges the positioning member upwardly or outwardly from the post to establish its seat, this movement into the second predetermined position being automatic in character, as will hereinafter be more particularly described.

In the assembly of the mechanism above described, the pin 25 is inserted in the central opening in the positioning member 23 whereafter this assembled unit is passed through the threaded end of the bore 20 to a position such that the pin 25 seats in the arcu-

ate recess provided for it at the top of the post in the head thereof, the threaded end of the member 23 facing outwardly or upwardly through the bifurcated portion to receive the screw from the receptacle 24. The plunger 22 is next disposed in the bore or aperture 20 of the post with the ball facing in a direction toward the positioning member whereafter the coil spring 21 is placed in the bore 18 with one end engaging the recess 27 of the plunger. The plug 19 is then screwed into position in the internally threaded portion of the shank 15 and is adjusted or tightened to a position such that the ball bearing 29 of the plunger 22 tensionally engages an arcuate portion of the positioning member 23. A sufficient amount of tension is provided by the compression of the spring 21 to hold the weight of the receptacle and the contained fountain pen in an inclined position, the plunger urging the positioning member upwardly or outwardly from the post through the bifurcated portion thereof so as to seat the pin 25 against its recess or bearing.

The receptacle 24 may be moved into various positions, for example, such as is shown in the drawing that the pen may rest so as to be readily grasped by the hand in a position preparatory to writing without a subsequent adjustment to any particular style. However, it may be desired to move the receptacle to a position such that the pen is pointed to a second person seated on the opposite side of a desk for the convenience of the latter. Ofttimes the bases are so large as to prevent a turning movement thereof and, therefore, the receptacle may be swung very readily. Further, it may be desirable to revolve the receptacle around the base in order to accommodate a group of users seated around the desk. The post in this instance may be manually rotated in the aperture against the friction of the spring washers.

In the operation of the receptacle to its various angular positions it will be apparent that should the ball 29 not have a seating engagement with one of the scallops or arcuate portions of the positioning member 23 as when the receptacle 24 is out of a predetermined position, the center of the arc will be out of axial alignment with the plunger and will thereby present a cam surface to the plunger whereby the latter is urged by its spring 21 to seat in one of the arcuate portions to pivot the receptacle into a predetermined position. Thus, in changing from one position to another it is only necessary to give the receptacle an initial movement whereafter it will be automatically changed into a predetermined second position. It is, of course, to be understood that as many scallops may be provided as the number of positions may be desired so that any number from one up may be had.

As a result of this invention it is possible to assemble or disassemble the above construction with comparative ease and by reason of assembling the positioning member and pen from within the post no unsightliness is presented to view and the post is lowered to a minimum. This, of course, is very desirable since the device of this invention is one of ornamentation as well as of great utility. All of the operating mechanisms necessary for accomplishing the desired results are concealed from view. Further, the ball bearing provided for engagement with the positioning member permits the screw plug 19 to be tightened up to a greater degree and to have a greater spring compression to accommodate the same degree of manual force for movement of the receptacle. This latter is desirable in that in many instances the adjustment screw 19 for determining the compression of the spring 21 is set at the factory before shipment and may be completely covered up and prevent subsequent adjustment by the user. One instance in which the adjusting means is not accessible subsequent to the assembly thereof at the place of manufacture is wherein the recess in the base is comparatively great, the base being a statutory object several inches thick. The post is uniform for all desk sets and extensions are provided for insertion in the recess for engagement with the external screw member of the post. The extension, therefore, covers the adjusting screw or mechanism which is controlled thereby.

While but a single embodiment of this invention is herein shown and described, it is to be understood that various modifications thereof may be apparent to those skilled in the art without departing from the spirit and scope of this invention and, therefore, the same is only to be limited by the scope of the prior art and the appended claims.

I claim:

1. A supporting means for the pivotally mounted fountain pen receptacle of a desk stand comprising a recessed member having a spring pressed plunger in the recess thereof, said plunger having movable means thereon for engagement with said receptacle for holding the same in adjusted positions.

2. A supporting means for the pivotally mounted fountain pen receptacle of a desk stand comprising a recessed member having a spring pressed plunger in the recess thereof, said plunger having roller means thereon for engagement with said receptacle for holding the same in adjusted positions.

3. A supporting means for the pivotally mounted fountain pen receptacle of a desk stand comprising a recessed member having a spring pressed plunger in the recess thereof, said plunger having a ball mounted at the upper end thereof for engagement with

said receptacle for holding the same in adjusted positions.

4. A supporting means for the pivotally mounted fountain pen receptacle of a desk stand comprising a recessed member having a spring pressed plunger in the recess thereof, said plunger having a ball mounted to rotate in the upper end thereof for engagement with said receptacle for holding the same in adjusted positions.

5. A supporting means for the pivotally mounted fountain pen receptacle of a desk stand comprising a recessed member having a spring pressed plunger in the recess thereof, said plunger having a recess at its upper end to receive a ball free to rotate, and means for preventing displacement of said ball, said ball engaging said receptacle for holding the same in adjusted positions.

20 6. A supporting means for the pivotally mounted fountain pen receptacle of a desk stand comprising a recessed member having a spring pressed plunger in the recess thereof, said plunger having a recess at its upper end to receive a ball free to rotate, and means for preventing displacement of said ball, said plunger having a recess in its lower end for receiving said spring and said ball engaging said receptacle for holding the same in adjusted positions.

30 7. A supporting means for the pivotally mounted fountain pen receptacle of a desk stand comprising a recessed member having a spring pressed plunger in the recess thereof, said plunger having a ball mounted at the upper end thereof for engagement with a scalloped peripheral end of said receptacle for holding the latter in one of various predetermined positions.

40 In witness whereof, I have hereunto subscribed my name.

SAMUEL L. DAUGHERTY.
